TOY

Noel L. Case and John L. Dohanic, Girard, Pa., assignors to Louis Marx & Company, Inc., New York, N.Y., a corporation of New York

Application September 15, 1955, Serial No. 534,577

4 Claims. (Cl. 274—1)

This invention relates to toys, and more particularly to toy phonographs.

The problem of providing a satisfactory toy phonograph for use in dolls and other toys is difficult, because of the severe requirements. The phonograph must play in any position, for the doll or other toy may be held in different positions. The mechanism must provide for automatic resetting of the stylus from the last to the first record groove, for the phonograph ordinarily is inaccessible. In addition the phonograph must be compact in dimension, light in weight, inexpensive in cost, and rugged enough to withstand mistreatment and rough handling by children.

The primary objects of the present invention are to generally improve toy phonographs, and to fulfill the foregoing requirements.

To accomplish these general objects, and other more specific objects which will hereinafter appear, our invention resides in the toy phonograph elements, and their relation one to another, as are hereinafter more particularly described in the following specification. The specification is accompanied by a drawing, in which:

Fig. 1 is a perspective view showing a toy phonograph embodying features of our invention;

Fig. 2 is a longitudinal section taken approximately in the plane of the line 2—2 of Fig. 1;

Fig. 3 is a plan view looking in the direction of the arrows 3—3 of Fig. 2, with the cover removed;

Fig. 4 is a fragmentary section similar to Fig. 2, but showing the relation of the parts as the reset cam first engages the stylus arm;

Fig. 5 is a plan view similar to Fig. 3, but showing how the stylus arm is moved radially by the cam;

Fig. 6 is a fragmentary section similar to Fig. 4, but showing how the stylus arm is moved axially by the cam;

Fig. 7 is a plan view similar to Fig. 5, but showing the relation of the parts after completion of the reset operation;

Fig. 8 is a fragmentary section similar to Fig. 6, but showing the relation of the parts after completion of the reset operation;

Fig. 9 is a detail drawn to greatly enlarged scale; and

Fig. 10 is a perspective view similar to Fig. 1, but showing a modification.

Referring to the drawing, and more particularly to Figs. 7 and 8 thereof, the toy phonograph comprises a disc record 12, and a vibratile diaphragm 14 which is disposed in a plane generally parallel to the plane of the disc record 12. A stylus 16 engages the record 12, and a rigid stylus arm 18 extends from the record to the diaphragm 14. The stylus arm 18 is pivoted on diaphragm 14, in order to permit the stylus 16 to traverse the record as the stylus tracks in the sound groove 20 of the record. The pivoted connection between the stylus arm 18 and the diaphragm 14 includes a flat enlargement 22 formed rigidly with the stylus arm 18 and bearing against the diaphragm 14. It further comprises a resilient means 24 for holding the disc 22 and dia-

2

phragm 14 together. In the particular construction here shown the pivoting action is provided by an extra long eyelet 26, and the resilient means 24 is a small compression spring surrounding the eyelet 26 and bearing 5 against the enlargement 22, and thus functioning to hold the parts together.

It will be understood that the recording groove 20 is of the hill-and-dale type, so that the stylus vibration is transverse to the plane of the record. This vibration 10 is transmitted to arm 18 with its enlargement 22, and thence to the diaphragm 14, which accordingly is vibrated to reproduce the sound recorded on the record.

The record 12 is rotated by a shaft 30. A cam 32 is fixedly secured to the shaft 30 at a point spaced from the record 12. A cam follower 34, in this case a short lug or finger, is formed on the stylus arm 18 for co-operation with the cam 32. The cam is shaped to act axially and radially. The small radius part 36 of the cam is nearer the record 12, and the cam is so dimensioned that the large radius part 38 turns freely beyond or above the stylus arm 18 during the playing of the record, until finally when the stylus arm has moved in to approach the innermost groove, the cam follower finger 34 reaches and engages the small radius part 36 of the cam which comes beneath the finger 34 (Figs. 3 and 4). Thereupon the cam separates the stylus axially from the record, as is indicated by the change from Fig. 4 to Fig. 6 of the drawing.

The cam also moves the stylus arm radially outward, 30 as is shown by the change from Fig. 3 to Fig. 5 of the drawing. Finally, when the stylus arm has been moved all the way out, the large radius part 38 of the cam passes the follower 34, as shown by the change from Fig. 5 to Fig. 7 of the drawing, and this permits the stylus to re-engage the record at the outermost grooves, 35 as shown by the change from Fig. 6 to Fig. 8 of the drawing. It will be understood that the record may have a high pitch starting groove outside the main body of closely spaced recording grooves 20, and a high pitch finishing groove inside the main body of recording grooves. This eliminates the need for precision in placing the stylus at the beginning and end of the record, and the actual hill-and-dale recording may be confined to the main body of grooves 20, so that the high pitch starting and finishing grooves are used only for the 40 mechanical resetting operation. No attempt has been made to show on the drawing the actual pitch and differences in pitch of the grooves.

In the present case the shaft 30 is driven in rather elementary fashion by a crank 40. For low cost a shaft may be bent to form it into a crank-shaft. A crank drive is preferred because of its simplicity and low cost, even though it has the disadvantage of variable pitch when the speed is varied. However, even that has a compensating advantage in that it affords amusement to most children, who experimentally operate the toy at different speeds in order to hear the great change in sound.

Referring to Fig. 1, it will be seen that the casing 42 is a relatively flat casing with the crank 40 projecting from one face. The diaphragm 14 is preferably mounted in the 60 same face of the casing, for then the sound is emitted from the side of the toy that provides access to the crank. For example, if the phonograph is mounted at the back of a doll with the crank projecting from the back of the doll, sound is emitted at the same side of the doll, and there is no need to provide for sound discharge from the other side of the phonograph through the body of the doll, which ordinarily is stuffed and thus tends to inhibit sound discharge.

Considering the illustrated structure in greater detail, 70 the casing 42 may be molded out of a suitable plastic material, and the front face 44 and the complete periph-

eral wall 46 may be integral. The opposite or open face may be closed by a suitable cover 48, which may consist of cardboard, fibreboard or the like, cemented or otherwise secured to the edge of the peripheral wall 46. Cover 48 is applied as a final step in the assembly of the phonograph.

Diaphragm 14 may be made of thin sheet metal, fibreboard, or other suitable vibratile material. The edge is received downwardly from above in an annular shoulder or step 50 (Fig. 2) molded in the wall 42 of the case. It is secured in position in any desired fashion, one method being to displace a series of spots of plastic material over the edge of the diaphragm by means of a hot tool, as is indicated at 52.

The crank shaft 30 is secured in a bushing or hub 54, shown to enlarged scale in Fig. 9. This is formed with an outer part 56, an intermediate part 58, and an inner part 60 which is square in shape. The intermediate part 58 is rotatably received in a mating hole in casing wall 44. The outer part 56 rests against the outside of the casing wall 44 (Fig. 8). The disc record 12 has a square hole at its center, which is received over the square portion 60, thus insuring that the parts will rotate together. The parts are held together by a spring nut 66. The intermediate part 58 is preferably slightly greater in thickness than the thickness of casing wall 44, thus providing a slight clearance between record 12 and wall 44, in order not to bind the record against rotation. The hub 54 may be molded of a plastic material, or may be diecast. Keys 62 (Figs. 4 and 6) are formed on shaft 30, and these keys are forced into mating slots 64 (Fig. 1) in hub 54.

To assemble the parts the crank shaft with its hub 54 are inserted in the casing; the record 12 is slipped over the inner end of the shaft and is seated on hub 54; following which a friction spring nut or so-called "speed nut" 66 is pressed down over the shaft until it bears rather tightly against the record.

The cam 32 is added subsequently. For this purpose the end of shaft 30 preferably is deformed to provide four keys in cruciform section, and the hole in the cam is preferably given a mating configuration. When the cam is pressed over the end of the shaft the latter may be upset or riveted to permanently secure the cam rigidly in position on the shaft.

The stylus arm 18 may be assembled with diaphragm 14 before securing the diaphragm in the casing. If this has not been done, the stylus arm may be added at any desired time, along with the eyelet and compression spring, following which the small end of the eyelet is spread or riveted to complete the assembly.

Tone arm 18 may be molded out of any one of the many suitable molding plastics, and in such case the enlarged area or disc 22 and the cam follower finger 34 are preferably molded integrally with the arm 18.

In the drawing it will be seen that the diaphragm 14 is laterally or sidewardly displaced from the record 12. However, they may partially overlap for compactness, as here shown.

If desired, the area of the diaphragm may be increased instead of being smaller than that of the record. Such a modified design is shown in Fig. 10, in which diaphragm 74 is substantially larger than the diaphragm 14 previously referred to. The diaphragm may be given a dimension substantially equal to that of the record, in which case the side edges of the casing may be made parallel, as shown at 76 in Fig. 10. Otherwise the construction in Fig. 10 is the same as that previously described.

It is believed that the construction of our improved toy phonograph, as well as the advantages thereof, will be apparent from the foregoing detailed description. It will also be apparent that while we have shown and described our invention in preferred forms, changes may be made in the structures shown, without departing from the scope of the invention, as sought to be defined in the following claims.

We claim:

1. In a toy phonograph comprising a crank shaft and crank for turning the same, a disc record on said crank shaft, a diaphragm disposed in a plane generally parallel to the plane of the disc record, a stylus and a stylus arm on the side of the record remote from the diaphragm and extending from the diaphragm to the record, said stylus arm being pivoted on said diaphragm by a pivot perpendicular to said diaphragm to permit the stylus to traverse the record, the pivoted connection between the stylus arm and the diaphragm including a flat enlargement forming a part of the arm and bearing against a mating flat part of the diaphragm, and stylus reset mechanism on said crank shaft, said parts being housed in a relatively flat casing having main front and back walls, said diaphragm and record being immediately adjacent the front wall of the casing, said stylus arm and said reset mechanism being located between the back wall on one side and the diaphragm and record on the other side, and said crank projecting from the front wall of the casing for rotating said record.

2. In a toy phonograph comprising a crank shaft and crank for turning the same, a disc record on said crank shaft, a diaphragm disposed in a plane generally parallel to the plane of the disc record, a stylus and a stylus arm on the side of the record remote from the diaphragm and extending from the diaphragm to the record, said stylus arm being pivoted on said diaphragm by a pivot perpendicular to said diaphragm to permit the stylus to traverse the record, the pivoted connection between the stylus arm and the diaphragm including a flat enlargement forming a part of the arm and bearing against a mating flat part of the diaphragm, and stylus reset mechanism on said crank shaft, said parts being housed in a relatively flat casing having main front and back walls, said diaphragm being secured to the front wall of the casing, a part of said diaphragm overlapping a part of the record for compactness, the overlap being less than the radius of the record, the record being just inside the casing wall and diaphragm, said stylus arm and said reset mechanism being located between the back wall on one side and the diaphragm and record on the other side, and said crank projecting from the front wall of the casing for rotating said record.

3. A toy phonograph comprising a crank shaft and crank for turning the same, a disc record secured to and turned by said crank shaft, a diaphragm disposed in a plane generally parallel to the plane of the disc record, a stylus and a stylus arm on the side of the record remote from the diaphragm and extending from the diaphragm to the record, said stylus arm being pivoted on said diaphragm by a pivot perpendicular to said diaphragm to permit the stylus to traverse the record, the pivoted connection between the stylus arm and the diaphragm including a flat enlargement forming a part of the arm and formed rigidly with the stylus arm and bearing against a mating flat part of the diaphragm, a cam fixedly secured directly to said crank shaft at a point spaced from said record and on the same side of the record as the stylus arm is located, a cam follower formed on said stylus arm for cooperation with said cam, said cam being shaped to act axially and radially, the small radius part of the cam being nearer the record than the cam follower, the large radius part of the cam being further from the record than the cam follower, said cam being so dimensioned that the large radius portion of the cam turns freely beyond the stylus arm until the latter has moved from the outer to the inner grooves, at which time the cam follower engages the small radius part of the cam, whereupon the cam separates the stylus axially from the record and moves it radially outward to the outer grooves of the record and there releases it to re-engage the record, said parts being housed in a relatively flat casing having main front and back walls, said diaphragm and record being immediately adjacent the front wall of

the casing, said stylus arm and said reset mechanism being located between the back wall on one side and the diaphragm and record on the other side, and said crank projecting from the front wall of the casing for rotating said record.

4. A toy phonograph comprising a crank shaft and crank for turning the same, a disc record secured to and turned by said crank shaft, a diaphragm disposed in a plane generally parallel to the plane of the disc record, a stylus and a stylus arm on the side of the record remote from the diaphragm and extending from the diaphragm to the record, said stylus arm being pivoted on said diaphragm by a pivot perpendicular to said diaphragm to permit the stylus to traverse the record, the pivoted connection between the stylus arm and the diaphragm including a flat enlargement forming a part of the arm and formed rigidly with the stylus arm and bearing against a mating flat part of the diaphragm, a cam fixedly secured directly to said crank shaft at a point spaced from said record and on the same side of the record as the stylus arm is located, a cam follower formed on said stylus arm for cooperation with said cam, said cam being shaped to act axially and radially, the small radius part of the cam being nearer the record than the cam follower, the large radius part of the cam being farther from the record than the cam follower, said cam being so dimensioned that the large radius portion of the cam turns freely beyond the stylus arm until the

latter has moved from the outer to the inner grooves, at which time the cam follower engages the small radius part of the cam, whereupon the cam separates the stylus axially from the record and moves it radially outward to the outer grooves of the record and there releases it to re-engage the record, said parts being housed in a relatively flat casing having main front and back walls, said diaphragm being secured to the front of the casing, a part of the diaphragm overlapping a part of the record for compactness, the overlap being less than the radius of the record, the record being just inside the casing wall and diaphragm, said stylus arm and said reset mechanism being located between the back wall on one side and the diaphragm and record on the other side, and said crank projecting from the front wall of the casing for rotating said record.
